HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,110,356.

Specification of Letters Patent.

Patented Sept. 15, 1914.

Application filed May 7, 1913. Serial No. 766,026.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates chiefly to typewriting machines, though it is also applicable to other sorts of machines and it has for its principal object to provide a simple, convenient and efficient means for numbering lines of writing produced by typewriters, adding machines or other printing machines. In fact, my invention is capable of adaptation to various situations where paper or other similar material is either fed past a fixed point or else a piece of mechanism of some sort is fed along the material.

To the above and other ends my invention consists in certain features of construction and combinations and arrangements of parts, all of which will be fully set forth herein and particularly pointed out in the claims.

The specific embodiment of my invention illustrated in the drawings, consists of a device for numbering the lines of writing on sheets of paper by a Monarch typewriter. In this typewriter the paper is fed through the machine from one line space position to another. In some other sorts of typewriters the printing mechanism is fed from one line space position to another along the paper. In either event my device would be mounted on the paper feed element that did not hold the paper.

In the accompanying drawings, all of which are on an enlarged scale, Figure 1 is a fragmentary front-to-rear vertical sectional view of enough of a Monarch typewriter carriage to illustrate the application of my invention thereto, my line numbering device being shown in side elevation. Fig. 2 is a front-to-rear vertical sectional view through said line numbering device about on the line α — α of Fig. 5. Fig. 3 is a diagram to illustrate the principle of the gear-

ing which controls the number wheels. Fig. 4 is a front view of the line numbering attachment and a few associated parts. Fig. 5 is an axial sectional view of the numbering mechanism. Fig. 6 is a view of one of the number wheels. Fig. 7 is a view to illustrate the relative positions in which the several numbers are printed.

The Monarch typewriter carriage comprises a transverse back bar or main bar 1 from which two brackets 2 project toward the front of the machine, one bracket at each end of the bar. Said brackets have journaled therein the shaft 3 of a roller platen 4 with which platen coöperate certain paper feed devices, most of which are not shown in the drawings, but which comprise feed rollers, a paper apron or deflector and other devices well known in the art. These may be said to include a platen scale plate 5, which is mounted on certain arms not shown, so as to stand in the relation to the platen illustrated in Fig. 1. The paper feed mechanism or paper controlling mechanism also includes certain paper fingers and associated devices, mounted on a rod 6, which rod extends from one of the brackets 2 to the other above the platen. Said bar 6 is connected to brackets 7 that extend upward from the brackets 2, and said rod has its ends bearing against the inner faces of said brackets 7 to each of which the rod is secured by means of a screw 8 passing through the bracket and threaded into the end of the rod. This rod also is usually formed across each end with a rib or spline that fits in a suitable groove in the bracket 7 so as to lock the rod 6 against turning. Said rod is, however, detachable from the carriage by removing the screws 8, and when said rod is detached, my numbering device and the ordinary left hand paper finger device, are readily interchangeable by slipping over the end of the rod.

The feeding of the paper from one line space position to another, is effected in the Monarch machine by means including a line space handle 10 projecting upward from the forward end of a rocking member 11, which

is controlled by a restoring spring 12. When the handle 10 is pushed toward the right, the shaft or member 11 is rocked and a line space pawl 13 is suitably operated against 5 a ratchet wheel, not shown, which results in the turning of the platen a suitable distance to space between lines. The distance through which the platen is turned at each 10 operation of the handle 10, can be varied by means of a device 14 which need not be here specifically described but which is well known in the art. In the Monarch machine this device is capable of setting the apparatus to space a single ratchet tooth distance or a distance of either two or three ratchet 15 teeth, as desired. The great bulk of typewriting is done with a spacing equal to two ratchet teeth or what is commonly called "double spacing", and my attachment is, in 20 the specific instance illustrated in the drawings, adapted to number correctly the lines of writing thus double spaced. It will, of course, be understood that nothing more will be required than a change in the dimensions of parts to adapt the mechanism for 25 other spacings.

My line numbering device comprises a support 15 mounted on and adjustable along the paper finger rod 6 of the typewriter. 30 This support consists of an arm which, except for its adjustability lengthwise of the rod 6, is rigid and is rigidly mounted on said rod from which it extends first upward and thence toward the front of the machine, 35 being similar in many respects to, and, except as to its forward end, it may be identical with, the corresponding part of the paper finger device ordinarily employed on the Monarch typewriter. The rod 6 is 40 formed on its under side with a longitudinal groove 16 in which is adapted to slide a spline 17, which, in the present instance, is substantially identical with the corresponding part connected with the Monarch paper 45 finger arm. This spline by its elasticity makes a frictional resistance to any motion of the support 15 lengthwise of the rod 6 but permits said support to be slid along said rod by the application of a little force; 50 and said spline also prevents turning of said support about said rod. In short, the support 15 is mounted on and adjustable along the rod 6 in a manner substantially identical with the support of the ordinary Monarch 55 paper finger device and, as will presently appear, my line numbering device is, in addition to its numbering function, adapted to perform also the functions of the said Monarch paper finger device.

60 A block or frame 18 has two parallel, rearwardly directed arms 20 which embrace the forward end of the support 15, to which said arms are pivoted by means of a pivot

pin or shaft 21. Said block or frame has also two forwardly directed arms 22 offset 65 toward the right from the parallel arms 20 and connected at the back by a sort of yoke bar 23, Fig. 2. The numbering mechanism is mounted in these arms 22, being supported for the most part on a fixed axle 24, 70 Fig. 5, which is inserted between the two arms 22 to which it is secured at one end by a screw 25, and at the other end by a screw 26, said screws passing through the respective arms 22 and threaded into the ends 75 of the axle 24. The screw 26 has its head elongated and formed as shown to constitute a handle by which to swing the frame 18 about its pivot 21.

On the right-hand part of the axle 24 80 there is journaled a units number wheel 27 having a hub 28 that extends over to the right-hand arm 22. This number wheel 27, as best shown in Fig. 6, contains two types 85 30 and 31, diametrically opposite to each other, the former printing the "0" and the latter the figure "5", and the former offset from the latter toward the left, as shown in Fig. 5.

The left-hand face of the wheel 27 is chamfered out to form a circular depression 32, Fig. 6, in which lies a tens printing wheel or ring 33, the chamber 32 being so located that the ring 33 lies at the left-hand side of the type 31 on the wheel 27. Said ring is 95 internally toothed so as to constitute a gear wheel that meshes with an elongated pinion 34 rigidly secured on or made integral with the axle 24. A second internally toothed tens printing ring 35 also meshes with the 100 pinion 34 at the left of the wheel 33, and said wheel 35 lies at its periphery just at the left of the type 30 on the wheel 27. A member 36 is journaled on the axle 24 at the left of the wheels 33 and 35, said member 105 itself constituting a wheel which is chambered out on its right-hand face similarly to the wheel 27 but oppositely, the wheel 35 lying in such chamber and being diametrically opposed to the wheel 33 when 110 considered with relation to the axle 24. The two wheels 27 and 36 are connected to rotate together by dowels 37, Fig. 2, that engage holes 38, Fig. 6. By means of these 115 dowels the two wheels 27 and 36 are connected so as to act practically as a single wheel. It will be perceived that if this compound wheel be caused to rotate about the axle 24 the wheels 33 and 35 will revolve about said axle and about the pinion 120 34 after the fashion of internal planetary gears. The walls of the chambers 32 will cause them to revolve about the axle and their engagement with the fixed pinion 34 will cause them to rotate within said chambers.

In order to rotate the wheels 27 and 36, a wheel 40 is journaled on the hub 28 of the wheel 27 and said wheel 40 is provided with a circumferential tire or covering 41 of rubber or similar material adapted to be turned by the paper on the platen after the fashion of a paper feed roller. For reasons that will presently appear, the wheel 40 is not rigidly connected with the wheel 27 but is connected with said wheel by means of a pin 42, Fig. 1, projecting from the wheel 27 into an arc-shaped slot 43 in the wheel 40, so that the two wheels 40 and 27 are constrained to turn together except that one can have an amount of lost motion with respect to the other, measured by the length of the slot 43. In order normally to restore such lost position a second pin 44 projects from the wheel 27 into a longer arc-shaped slot 20 45 in the left-hand face of the wheel 40 and a coiled spring 46 is compressed between said pin 44 and one end of said slot 45, the construction being such as to hold the several parts normally in the relative positions 25 shown in Fig. 1.

The frame 18 is acted upon by a leaf-spring 47 secured to the upper surface of the arm 15 and the tension of which can be regulated by an adjusting screw 48 threaded into the said arm. The forward end of the spring 47 is so shaped and positioned as that it can engage the cross bar 50, Fig. 4, that connects the two arms 20, either on top of said bar, as shown in said Fig. 4, or 30 in front of said bar, depending upon the position of said frame 18. When the parts are in the position shown in Figs. 1 and 4, the spring 47 presses the frame 18 downward and presses the wheel 40, 41 against the platen; but if the frame 18 be raised 35 as by the handle 26 until the spring 47 catches over the front edge of the bar 50, then said spring will yieldingly hold the frame in its elevated position out of contact 40 with the platen.

In order to determine a normal position of the compound wheel 27, 36, any suitable form of indicating device can be provided, such device preferably consisting of a yielding 45 deterrent. As here shown, especially in Fig. 5, a ball 51 is mounted in a cylindrical cap 52 which is threaded into the left-hand one of the arms 22 and said ball is pressed toward the right by a spring 53 compressed 50 between the ball and the end of the cap. A suitable depression is formed in the left-hand face of the wheel 36 so that the wheels can be turned to normal position by hand until the depression is engaged by the ball 55 when the wheels will be held in that position yieldingly.

An endless ink ribbon 54, Fig. 4, is conducted around the printing wheels by a

curved guide 55 and said ribbon also runs over a roller 56, Fig. 1, journaled on the 65 shaft 21 which is prolonged toward the right for that purpose. Said guide 55 is secured to the yoke bar 23, and it terminates below the type wheels so as to allow the ribbon to be pressed by said wheels against 70 the platen. The roller 56 is retained on the shaft 21 by a headed screw 56^a threaded into the end of the shaft. The wheel 33 has on it four types 57, 58, 59 and 60; these types are adapted to print respectively "0", "1", 75 "2" and "3" as will be best understood by reference to Figs. 2 and 3. The wheel 35 also contains four types 61, 62, 63 and 64 adapted respectively to print the numerals "1", "2", "3" and "4".

When the numbering device is not in use it will stand in a position where the printing wheels are out of contact with the platen, and in this position of the parts the spring 46 will cause the wheel 40 to assume 80 the position with respect to the wheel 27 indicated in Fig. 1. When a piece of paper is put into the machine to be written upon, it is first brought to the position for writing the first line on said piece of paper; afterward the numbering device is depressed by 85 means of the handle 26 until the wheel 41 is pressed against the paper by the spring 47. In the Monarch machine the printing is on the front face of the platen, horizontally in front of the axis of the shaft 3, and it will be perceived from an inspection of Fig. 1 that my numbering wheels engage the platen a little distance above 90 the writing line. It will also be perceived by an inspection of Figs. 2 and 3, that in the initial position of the parts no one of the types is in position to print. When the numbering device is moved down to its 95 position shown in Fig. 1, and the writing upon the paper is proceeded with, the paper will be line spaced from time to time by means of the handle 10 and its connected devices. As the platen turns the wheel 40 will be turned by it until the rear end of 100 the slot 43 reaches the pin 42 when the wheel 27 will be forced to turn with the wheel 40 and the ball 51 will be forced out of its socket in the wheel 36, after which the wheels 40, 27 and 36 will all rotate together, the friction due to the pressure of 105 said ball 51 and to other causes, preventing the spring 46 from turning the numbering wheels. A certain amount of such rotation will bring the type 31 to position to print 110 on the paper that is passing beneath the type wheels. The depression for the ball 51 is so located and the slot 43 is so proportioned that the type 31 will reach the printing position at the same time that the fifth 115 written line reaches the position correspond-

ing to the position of the type 31. The depression for the ball 51 is so located and the slot 43 is so proportioned that the type 31 will reach the printing position at the same time that the fifth 120 written line reaches the position correspond- 125

ing to the point of tangency between the platen and the numbering wheels so that the "5" will be printed on the paper. As shown in Fig. 3, the type 57 on the wheel 33 initially stands a little in advance of the type 31 on the wheel 27. The wheel 33, however, not only revolves around the axle 24 but also has a retrograde rotation due to its engagement with the pinion 34 and this is such that by the time the type 31 reaches printing position the type 57 will be directly in line with said type 31 and the figures "05" will be printed in the position indicated at *a*, Fig. 7, the "0" being printed by the type 57 and the "5" by the type 31.

The wheel 40 is of such circumference that it receives a complete rotation for each ten lines of writing, and, therefore, by the time the tenth printed line reaches the point of tangency between the platen and the numbering devices the type 30 will be in printing position, and the type 61 is so positioned on the wheel 35 that at the same time that the type 30 is in printing position said type 61 will be in line with said type 30 and just at the left of it so that the number "10" would be printed as shown in Fig. 7 at *b*, the "1" being printed by the type 61 and the "0" by the type 30. At the end of the next five letter space operations the type 31 will again be at printing position and by this time the type 58 will have so far retrograded by rotation of the wheel 35 that it will be by the side of the type 31 and the number "15" will be printed as shown in Fig. 7 at *c*. The next printing will be the number "20" shown in Fig. 7 at *d*, the "2" being printed by the type 62 and the "0" by the type 30. The number "25" as shown at *e*, in Fig. 7, will be printed by the type 59 and the type 31 and so on as far as the writing extends. The units of the numbers, namely the "0" and "5" are printed by the wheel 27, and the tens by the planetary wheels. The column of numbers is staggered down the page as shown in Fig. 7, because some of the tens are printed by the wheel 33 and the alternate tens by the wheel 35.

When a page of writing is complete and drawn out of the machine the wheel 40 will continually turn with the paper as long as said paper runs under it. At the end of the numbering operation the operator lifts the frame 18 so as to bring the several wheels out of contact with the platen, at which time the spring 46 will immediately bring the wheel 40 back to the relative position shown in Fig. 1. The operator then by hand turns the wheel 27, 36 until the printing wheels are restored to normal position ready for the writing of another sheet of paper.

The gearing shown in the present instance is such that each of the wheels 33, 35 will re-

ceive a complete rotation upon four complete rotations of the wheel 27, 36. In the present instance the pinion 34 is shown with ten teeth and each of the wheels 33 and 35 with forty teeth.

A paper finger or guide plate 65 is mounted on the arm 15 after the ordinary fashion of this part of the Monarch typewriter. The upper part of said plate 65 is secured to a sheet metal device 66 so folded as to have two branches that embrace the arm 15 to which they are pivoted at 67 and a spring 68 presses the parts downward to press the paper finger against the platen. This paper finger or guide plate can, of course, be formed in various ways as far as my invention is concerned, but as here shown it is made wider than usual and is formed with an opening 70, Fig. 4, through which the various printing wheels and the ink ribbon can project in order to make contact with the platen or the paper.

It will be perceived that the mechanism which has been described is adapted to perform all of the functions of the ordinary paper finger and marginal feed roller devices, the wheel 40, 41 taking the place of the ordinary small marginal paper feed roller.

In Fig. 1 I have shown in dotted lines a type bar 71 having a type block 72 thereon in printing position. The point at which the type touches the platen is, of course, the printing point.

In order for types to print clearly on a cylindrical platen by impact after the fashion of the types on the type block 72, it is necessary that said types be formed with a concave face to conform to the convex curvature of the platen. My numbering device does not print by this sort of impact but prints by a rolling action. The faces of my types are therefore convex, partaking merely or substantially of the general cylindrical form of the wheels which carry them. It is much easier to make a number of types of this character on a single type carrier and to have them all work properly than to make a number of concave types adapted for printing by impact.

Various changes can be made in the details of construction and arrangement without departing from my invention.

What I claim as new and desire to secure by Letters Patent, is:—

1. In a machine of the character described, the combination of a platen, a paper feed roller, and a line numbering wheel actuated from said paper feed roller.

2. The combination of a platen, a paper feed roller, and line numbering wheels actuated from said paper feed roller and having lost motion connection therewith.

3. The combination of a platen, means for printing on said platen, means for turning said platen for line spacing, and a line numbering wheel located above the printing line 5 and turned by a rolling action against the paper at each actuation of said line spacing means.
4. The combination of a platen, means for writing on said platen, line spacing means, 10 a roller pressed into contact with the paper and arranged to be turned at each actuation of said line spacing means, and line numbering devices operated by said roller.
5. The combination of a platen, printing 15 instrumentalities, line spacing means, a paper finger, and line numbering devices adjustable with said paper finger along said platen.
6. The combination of a platen, a paper finger, a paper finger rod, and a line numbering 20 device adjustable with said paper finger along said rod.
7. The combination of a platen, a paper finger rod, a line numbering device adjustable along said rod, and means for pressing 25 said device toward or from said platen to cause it to be operated by said platen or not as desired.
8. The combination of a platen, line spacing means, and a line numbering device comprising a paper feed wheel or roller movable toward and from said platen, and spring means for pressing said roller against said platen.
9. The combination of a platen, and an 35 automatic line numbering device movable toward and from said platen into and out of working position and comprising number printing wheels having a rolling action on said platen.
- 40 10. The combination of a platen, means for writing a line along said platen, line numbering mechanism offset from said writing line, and means for measuring off the starting distance of said line numbering device in accordance with the extent to which said device is offset from said writing line.
11. The combination of a platen, means 45 for writing a line along said platen, line spacing means, a line numbering device offset from said line of writing, means for measuring off the starting distance of said line numbering device according to the distance that said device is offset from said writing line, and a spring for restoring said measuring means.
12. The combination of a platen, line spacing means, a line numbering device actuated at each operation of said line spacing means, and indicating means to give the correct 50 starting position of said line numbering device.
13. The combination of a platen, line spacing means, a line numbering device actuated at each operation of said line spacing means, and a detent to give the correct starting position of said line numbering device.
14. The combination of a platen, printing instrumentalities, line spacing means, and a line numbering device operated by frictional engagement with the platen or with the paper 55 thereon.
15. The combination with a platen, of number printing wheels arranged to roll against said platen, and means for causing relative motion between said wheels to change the numbers printed.
16. The combination of a platen, a paper finger having an opening therein, and a printing device acting through said opening.
17. The combination of a platen, a paper finger having an opening therein, and a printing wheel acting through said opening.
18. The combination of a platen, a paper finger having an opening therein, and a line numbering device acting through said opening.
19. The combination of a cylindrical platen, a plurality of number printing wheels coöperating with said platen by rolling action, and means for effecting relative turning motion between said wheels to change the numbers printed.
20. The combination of a platen, a roller turned by frictional contact with said platen, a plurality of number printing wheels, and means whereby said roller causes said wheels to print on the paper on said platen by rolling action and also causes relative turning movements between said wheels to change the numbers.
21. The combination of a platen, a paper finger, and a line numbering device associated with said paper finger and adjustable therewith lengthwise of the platen.
22. The combination of a platen, printing instrumentalities, a line numbering device having a rolling action on said platen, and an ink ribbon between said numbering device and the platen, said ink ribbon fed by said rolling action.
23. The combination of a platen, printing instrumentalities, line spacing means, a line numbering means comprising a type wheel having a rolling action on said platen, and an ink ribbon interposed between said type wheel and said platen.
24. The combination of a platen, printing instrumentalities, line spacing means, a rotary line numbering wheel, a planetary number wheel revolving about the axis of rotation of the first mentioned number wheel, and means for turning said wheels by the operation of said line spacing means.
25. The combination of a platen, printing instrumentalities, line spacing means, a line numbering wheel, a planetary number wheel

revolving about the axis of rotation of the first mentioned wheel, a fixed pinion engaged by said planetary wheel, and means for turning said wheels by the operation of said line spacing means.

26. The combination of a platen, printing instrumentalities, line spacing means, a ring having internal gear teeth and having a plurality of numbers thereon for numbering the lines of writing, a fixed pinion engaged

by said gear teeth, and means operated by said line spacing means for revolving said ring about the axis of said pinion.

Signed at Syracuse, in the county of Onondaga and State of New York, this 5th 15 day of May A. D. 1913.
